(57) CLAIM

The ornamental design for a sofa, as shown and described.

DESCRIPTION

FIG. 1 is a front perspective view of the sofa showing my design.

FIG. 2 is top plan view thereof;

FIG. 3 is a back perspective view thereof;

FIG. 4 is a side view thereof; and,

FIG. 5 is an opposite side view thereof.

The broken lines shown on the sofa are understood to represent stitching.

1 Claim, 2 Drawing Sheets
